UNITED STATES PATENT OFFICE.

WILLIAM S. NEAD, OF STILLWATER, MINNESOTA.

INTERCHANGEABLE LINING.

1,358,387.

Specification of Letters Patent. Patented Nov. 9, 1920.

Application filed July 18, 1919. Serial No. 311,730.

To all whom it may concern:

Be it known that I, WILLIAM S. NEAD, a citizen of the United States, residing at Stillwater, in the county of Washington and 5 State of Minnesota, have invented a new and useful Interchangeable Lining, of which the following is a specification.

This invention relates to apparel and more particularly to interchangeable linings for coats, vests or the like.

In cold climates where the temperature reaches a low degree, fur lined coats are worn as a necessity, and it has been found in practical use, that often times a coat 15 having a fur lining must be discarded, because the coat proper has become worn beyond use.

It is therefore the object of the present invention to provide a removable lining, 20 and one which may be easily and quickly replaced by any person unfamiliar with tailoring.

A still further object of the invention is to provide a device of this character which 25 will be securely held in position on the coat, and not cause the coat to draw or present an irregular fit.

With the foregoing and other objects in view which will appear as the description 30 proceeds, the invention resides in the combination and arrangement of parts and in the details of construction hereinafter described and claimed, it being understood that changes in the precise embodiment of 35 the invention herein disclosed, may be made within the scope of what is claimed without departing from the spirit of the invention.

Referring now to the drawing in detail:

Figure 1 illustrates a side elevational 40 view of the front portion of a coat constructed in accordance with my invention.

Fig. 2 illustrates a side elevational view of the interior or lining of the coat.

Fig. 3 illustrates a sectional view taken 45 on line 3-3 of Fig. 1.

Fig. 4 is a sectional view 4-4 of Fig. 1.

Fig. 5 illustrates a sectional view taken on line 5-5 of Fig. 1.

Fig. 6 is a side elevational view of a 50 sleeve partly broken away.

Fig. 7 is a sectional view of the separable button used in connection with my invention, and;

Fig. 8 is a sectional view taken on line 55 8-8 of Fig. 6.

Referring now to the drawings in detail,

the reference character 5 designates the front portion of a coat having suitable reinforcing eyes 6 formed adjacent the front edge thereof, said eyes extending from a 60 point adjacent the upper edge of the coat, to a point in close proximity to the lower edge thereof.

The storm flap 7 has a portion of its upper edge sewed to the inner edge of the coat, 65 adjacent the upper edge thereof, the front, or forward edge 7' of the storm flap 7 being secured to the inner front edge of the coat by the line of stitching 8, the lower edge of the storm flap 7 being reinforced 70 and secured to the coat by the lower in-turned edge 9 of the coat proper, which in-turned edge 9, as shown embraces the extreme end of the storm flap 7 and secures the same against displacement by strain 75 directed to this point, when removing the coat.

The inner edge 10 of the storm flap 7 is provided with a series of button holes 11, which register with the reinforced eyes 6 80 of the coat proper, for purposes to be hereinafter more fully described.

Extending upwardly from the lower edge of the storm flap 7 is a line of spaced eyelets 12, which eyelets cooperate with the eyelets 13 formed in the leather strip 14 secured adjacent the lower front edge of the removable lining 15, for receiving the lacing cord 14', which lacing cord laces the lower end of the lining 15, and the storm 90 flap 7 together.

A lining 15, which may be formed of any warmth holding material, but preferably fur, is provided with a reinforcing strip 16 of coarse material, and sewed to the front 95 edge of the lining 15 by the line of stitching 15', said reinforcing strip being also provided with pairs of reinforced eyes 16' extending in spaced relation longitudinally thereof, and being arranged in such relation that the same will register with the button holes 11 formed in the storm flap 7 and the reinforced eyes 6 formed adjacent the front edge of the coat. As shown, the storm flap 7 overlies the reinforcing strip 16 to guard 100 against wind entering between the lining and the coat proper.

The collar 17, is formed of an inner member 18 and an outer member 19, sewed together along the top and end edges thereof 110 by the line of stitching 20, the inner member 18 being secured to the upper edge of

the lining, by the line of stitching 21 extending along the lower edge of the collar, the lower edge of the outer member 19 having a plurality of spaced eyelets 22 formed therein. These eyelets 22, coöperate with the eyelets 23 formed in the upper edge of the coat and receive the lacing cord 25 to draw the collar 17 into position on the upper edge 24 of the coat, and securely hold 10 the same in such position, the free end of the lacing cord 25 being sewed to the lining.

To facilitate the easy and quick dismantling and assembling of a coat constructed in accordance with the present invention, 15 separable buttons 25' are provided, and adapted to be positioned in the registering eyes of the reinforcing strip 16, eyes of the coat 5, and the button holes of the storm flap 7.

20 As shown by Fig. 7 each of the buttons comprises a head 26 having a metallic loop or eye 27 secured to the back thereof, and a securing button 28, having a hook member 29 coöoperating with the metallic loop 27. It will therefore be seen that when the buttons 25 are positioned in such registering openings, as before described, the elements of the coat are securely but removably held together.

The lining of the sleeve is indicated at 31, 30 and as shown by Fig. 6 of the drawings, the lining 31 is provided with a button 32, adjacent the lower edge thereof, which button accommodates the opening provided in the extension 30, the opposite end of said extension 35 being sewed to the inwardly extending hem 33.

In the construction shown by Fig. 8 of the drawings, it may be found desirable to provide the inwardly extending hem 30' 40 with suitable button-holes to receive the buttons 34, provided on the sleeve lining 35,

thus eliminating the necessity of stitching an extra piece to the hem.

In the initial construction of the coat, the inner eyelets of the respective pairs are employed to receive the button fastening means, but it has been found in use, that the lining often shrinks, with the result that the coat proper is drawn, and an unsightly fit is the usual result. When conditions described above occur it is only necessary to move the buttons to the next adjacent eyelet of the respective pairs, thereby shifting or adjusting the lining 16 with relation to the coat 5, thereby compensating for such shrinkage.

Having thus described my invention, what I claim is:—

In a garment, an outer member having a storm flap, said storm flap having a plurality of openings formed therein, adjacent one side edge thereof, and having a plurality of openings formed adjacent the upper edge thereof, a removable lining having a collar formed at the upper end thereof, said collar having a plurality of openings, lacing means passing through the openings in the garment adjacent the upper edge thereof, and through the openings of the collar for lacing the collar to the outer member, 7 said lining having buttons to be positioned within the openings formed adjacent the side edge of the body portion, and lacing means for securing the lower extremity of the lining to the storm flap.

In testimony that I claim the foregoing as my own, I have hereto affixed my signature in the presence of two witnesses.

WILLIAM S. NEAD.
